WORK SUPPORT ARRANGEMENT FOR
GRINDING AND DRESSING MACHINES

Emil F. Hager, Queens Village, N. Y.

Application November 14, 1945, Serial No. 628,433

17 Claims. (Cl. 51—124)

1

This invention relates to work grinding and dressing machines and more particularly to support arrangements for holding tools or other work at desired angles for movement relative to the grinding and dressing elements of such machines.

In some grinding and dressing machines such, for example, as disclosed in the U. S. Patent No. 2,144,095, the work support is made adjustable along a guide bar disposed parallel to the spindle and closely adjacent the grinding and dressing element carried by the spindle. In my copending application Serial No. 575,749, filed Feb. 2, 1945, I show an improved grinding and dressing machine wherein a work support guiding bar is disposed a distance away from the grinding and dressing elements outside the zone of flying particles produced by the grinding and dressing operations.

It is an object of this invention to provide work supporting means for use with either of the two forms of machines referred to above.

Another object of the invention is to provide improved work support means for grinding and dressing machines capable of supporting various forms of tools and other work at various angular positions in operative relation with the grinding or cutting elements of the machine.

The above and other objects of the invention will become more clearly understood from the following detailed description to be considered in connection with the accompanying drawings in which:

Fig. 1 is a plan view of a work grinding and dressing machine shown provided with a coupling attachment in accordance with my invention;

Fig. 2 is a fragmentary view in front elevation of the grinder machine of Fig. 1 with one of the work supporting means of this invention supported in the coupling attachment shown in Fig. 1;

Fig. 3 is a sectional view taken substantially along line 3—3 of Fig. 1, with the main work supporting means removed;

Fig. 4 is a cross sectional view taken substantially along line 4—4 of Fig. 3;

Fig. 5 is a plan view of another form of grinding machine provided with a second embodiment of the work supporting structure of my invention which I refer to as V block;

Fig. 6 is a front elevational view of the work supporting structure of Fig. 5 and Fig. 6A is a similar view of a modification;

Fig. 7 is a side elevational view of the work supporting means of Figs. 5 and 6;

Fig. 8 is a front elevational view of a further embodiment of the work supporting means of my

invention which I refer to as the center attachment;

Fig. 9 is a side elevational view of the center attachment of Fig. 8;

Figs. 10 and 11 are plan and end views, respectively of another supporting structure; and

Fig. 12 is a side view of a bracket that may be used with the structure of Figs. 10 and 11.

Referring to Figs. 1, 2, 3 and 4 of the drawings I show a base 1 upon which is mounted the grinder head 4. The head 4 includes bearings such as indicated at 6, Fig. 3, to support a spindle 7. The spindle 7 supports for rotation, grinding and dressing wheel elements 9 and 9a preferably of the character having working surfaces on the sides thereof. Each wheel element is partially covered with a guard 10. A liquid circulating system 11 directs cooling and cleaning liquid onto the working surfaces 12 of each of the elements 9 and 9a.

The base 1 includes an upturned marginal flange 13 to provide a catch basin for the liquid and the cuttings during grinding and dressing operations, the liquid and cuttings being removed by drain 14. Mounted outside the basin on arms 15 is a guiding bar 16 for a carriage 17 which supports a work supporting post 31. The carriage is adjustable along the bar 16 and may be locked thereto in any desirable position by means of locking screw 19.

The bar 16 is disposed parallel to the spindle 7. The frame of the carriage 17 is triangular as viewed in plan, Fig. 1, and two corners thereof are provided with bearing elements 20 and 21 which receive the bar 16 to guide the carriage along a true line parallel to the spindle 7. Toward the apex of the carriage is a depending leg 22 provided with a roller 23 which tracks upon a machined surface 24 on the base 1.

As shown in Fig. 4 the apex of the carriage 17 is provided with spaced shaft supporting elements 28 and 29 for rotatably and slideably supporting a member 30 which in turn pivotally supports a post 31. The post 31 is preferably supported with its longitudinal axis disposed transverse to the axis of the shaft supporting elements 28, 29. The member 30 is provided with a tubular socket 32 for reception of the lower end of the post 31, the post being locked in position by lock screw 33 Figs. 1 and 2. On the socket 32 is keyed a calibrated dial 34 over which is disposed a pointer 35 keyed to the post 31. This provides an angular indication of the adjusted position of the post 31.

The upper end of the post 31 is provided with

a work supporting clamp 38 and a lock screw 43 for securing the clamp in the desired angular position about pin 37 which is carried by post 31.

From the foregoing description it is clear that the post 31 may be adjusted to any desired angular position about its longitudinal axis and the work clamp 38 may be adjustable about an axis transverse to the longitudinal axis of the post 31. It will now be described how the post is made adjustable along an axis transverse to the longitudinal axis, or in other words, parallel to the axis of the spindle 7. It will also be described how this mounting provides for rocking movement of the post 31 toward and away from the spindle 7 so as to provide movement of the work being shaped relative to the surface 12 of the grinding element 9.

As shown in Fig. 4 a hollow shaft or sleeve 45 is held by screw 43b in supporting element 28 with a pusher pin 43 extending therethrough. The member 30 is secured to the sleeve 45 by a lock screw 41. A second shaft or sleeve 48 is held in position in the support 29 by a set screw 49a. Disposed in the sleeve 48 is a retraction spring 49 the outer end of which carries a thrust pin 50. Mounted in opposite ends of the member 30 are two thrust caps 51 and 52 having thrust points engaging pusher rod 46 and thrust pin 50 respectively. The inner end of the pusher rod 46 is engaged by a pin 53 held by crank 54 (see Fig. 3) carried by shaft 55. A second crank arm 56 secured to the shaft 55 is engaged by a threaded member 58 engaged by a threaded nut 57 and a packing unit 57a. This screw member 58 is preferably provided with a collar 58a having calibrations by which the extent of adjustments can be readily determined. The calibrated collar is held on with a ball and spring, the ball riding in an annular groove on the inner surface of the collar so that the collar is adjustable on member 58. An adjustable calibrated pin 58b is disposed adjacent collar 58a for determining the degree of axial movement of member 30 as screw 52 is turned.

By adjusting the screw 52 the crank arm is forced to the right as viewed in Figs. 2 and 4 thereby causing the pin 53 to actuate pusher rod 46 to the right. The pusher rod carries with it the member 30 thereby moving the post in a direction parallel to the axis of the spindle 7. This movement of the member 30 compresses spring 49. Retraction of the adjustment screw 58 permits the spring 49 to return the member 30 to the left maintaining the pusher rod 46 against the pin 53. It will thus be apparent that by adjusting the screw 52 forward and backward the member 30 is moved lengthwise of sleeves 45 and 48 relative to the carriage 17.

The member 30 when unlocked by releasing lock screw 47 is rotatable about the sleeves 45 and 48. This provides spaced bearing surfaces for the member 30 thereby enabling the operator to rock the member 30 and the work supporting post 31 carried thereby about the axis of the sleeves 45, 48. In order to limit the rocking movement of the member 30 the member is provided with a stop lug 61 secured thereto by lock screw 62, the lug 61 being engageable with a stop pin 63 adjustably supported on a projection 65 of the carriage 17.

The adjustment provisions for post 31 and clamp 38, Fig. 1, permit the positioning of the work such as tools at various predetermined angles relative to the surfaces 12 of the work shaping elements 9 and 9a. By manipulating

adjustment screw 58, the work may be moved into the cutting surface 12 while rocking the work to and fro across the face of the surface 12.

Having described a form of work supporting means such as disclosed in my aforesaid application (Serial No. 575,749), I will now describe a further form of work supporting means which may be mounted upon the end portion of rocking member 30 adjacent the stop lug 61, Fig. 4. 10 A coupler 70 is provided for this purpose, it having a split sleeve 71 which may be secured in adjusted position on the rocking member 30 by locking element 72. The coupler 70 also includes a second sleeve or socket 73 with lock screw 73a 15 for receiving in adjusted position, a post 74 similar to post 31. The post 74 is provided with a transverse opening 75 for reception of a rod 76, Fig. 2, of a work supporting structure 77. The rod 76 is locked in position by element 78. At 20 one end of rod 76 is a head 79 having a transverse opening for reception of a second rod 80. The rod 80 is held in the desired position by lock element 81. The rod 80 is provided with a plurality of different size spacer elements 83 and 25 a threaded abutment 82 receivable in a threaded aperture at the end of rod 80.

Work stock such as wheels, gears, cams, etc. may be clamped between the abutment 82 or one of the spacer elements 83 and another of 30 the spacer elements, one or more of the spacer elements being removed to receive the work stock on the rod of 80.

In work shaping apparatus it is frequently required that the work stock be properly positioned 35 so that the portion thereof to be cut or otherwise shaped, be held for a given angular relationship with respect to the working surface of the wheel 9a. This is accomplished by means 40 of a positioning device which includes split sleeve 84 adapted to be clamped by lock screw 85, Fig. 2, in desired position on post 74, or if desired, on rod 76, the sleeve being provided with an opening to receive an elongated element 86 adapted 45 to be locked in position also by element 85. The element 86 has a transverse opening 87 (Fig. 3) therethrough and an adjacent set screw 88 for securing a positioning finger 89 or if desired, a flat spring in desired relation with respect to work supported on rod 80.

50 In operation, it will be clear that with the coupler 70 clamped tightly on rocker member 30, the work supported by the rod 80 will be moved toward and away from the grinder wheel 9a cross-wise of the surface 12 thereof as the member 30 is rocked. It will also be clear that the work may be supported at any desired angle 55 with respect to the cutting surface 12 of wheel 9a. This angular adjustment being obtained by adjustment of post 74 about its longitudinal axis, by adjusting rods 76 and 80 longitudinally and 60 rotatably relative to their respective longitudinal axes. As previously pointed out the finger 89 may be adjusted to locate the end thereof in a position against which some part of the work 65 may be positioned. Thus, where like pieces of work are to be similarly shaped the operator may, for a given adjustment position of the work supporting post 74, rods 76, 80 and finger 89, quickly exchange one piece of work for another.

70 In Figs. 5, 6 and 7 I show an alternative embodiment of the invention wherein the work supporting structure may be mounted directly upon a rocking member comprising also a guide bar for adjustment of the structure parallel to the axis of the spindle. For example, the rocking

bar 90 may be of the character adapted to be mounted on the base 1 closely adjacent the grinder head 4. The bar 90 may be of the character disclosed in U. S. Patent 2,144,095 whereby turning adjustment of member 91 is adapted to move the bar 90 in one longitudinal direction or the other, while at the same time permitting the bar to be rocked about its longitudinal axis. The coupler for the work supporting structure may be similar to the coupler 70 but preferably is of the character shown in Figs. 5, 6 and 7. For example the coupler 94 is provided with a longitudinal bore to receive the bar 90, the coupler being provided with a lock screw 95 to secure it to the bar. The coupler 94 also includes a vertical socket 96 disposed at right angles to the bore and provided with a lock screw 97 to secure post 74 therein. The post 74 in this embodiment however is shown to support a different type of work supporting device 100 which I call the V block. In the apex of the V block 100 is a bore for retention of a rod 101, lock screw 102 being provided to hold the rod in adjusted position. One end of the rod 101 is provided with an opening to receive an elongated end piece 103 which is held in adjusted position by lock screw 104. The end piece is also provided with an adjustment screw 105 threaded on one end of the piece 103 for adjustment axially of the V block, the adjustment element being held in desired position by set screw 106. The V block is also provided with an upper clamp consisting of two threaded members 110 and 111 threadably received in openings provided in the sides of the block, the two pieces supporting a cross bar 112 which contains an adjustment screw 114 threaded therein in alignment with the apex of the block. If desired a second cross bar like bar 112 may be used at 115, or bar 112 may be located at 115. The upper clamp 110, 111 will be clear of the work supporting device 100.

From the foregoing description it will be clear that work stock may be adjusted longitudinally within the trough of the V block or inserted in the same position, front or back against screw 105, and clamped therein by screw 114. Thus held in position the work stock may be adjusted at different angles for forward and rearward movement relative to the wheel 9a, this adjustment being obtained by revolving post 74 and rod 109. If desired the work positioning structure including finger 89 may be supported either on the right hand end of rod 109 or on post 74.

In Fig. 6A I show a variation of the V block wherein the clamp screw 114a is supported by a cross piece 112a carried by a post 110a adjustable in an opening extending through a V block extension 110a to which rod 109a may be made integral. This clamp arrangement is easier and handier to manipulate than clamp 114 of Figs. 5 to 7, and also takes larger work stock 113.

In the embodiment shown in Figs. 8 and 9 a further variation of the work supporting structure is shown. The coupler is formed integral with the rocking member 130 which may be similar to rocking member 30, Figs. 1-4, or it may be secured to a rocking bar 90 as shown in Fig. 8. The rocking member includes a socket 173 for post 14 and a centrally located socket 131 which may support a work supporting post 31 similarly as shown in Figs. 1 and 2.

As shown in Figs. 8 and 9 the socket 113 supports post 74 in desired position, the post in turn being provided with adjustment rod 76 which supports a spacer rod 134. The spacer rod 134 in turn is provided with a pair of centering elements 135 and 136 each having a sleeve 137 and

a lock screw 138 by which they may be adjusted in desired position on rod 134. The outer end of each centering element may be provided with a pointed pin such as indicated at 139, held in a split sleeve 140 by lock screw 141. Preferably, however, I provide one of the centering elements with pin 139 and the other (136) with a releasable control 142 by which the work may be revolved easily for different cutting operations, and 10 also easily and quickly replaced.

also easily and quickly replaced. Control 142 includes a U-shaped bearing arrangement 143 and 144 at the upper end of centering element 136. An elongated centering pin 145 extends through bearings 143 and 144, the pin having a ring 146 keyed thereto for coaction with springs 147, whereby pin 145 is urged toward pin 139. Adjacent the pointed end of pin 145 is a driver 148 carried thereby to engage work and at the other end of pin 145 is a crank 149 whereby work can be revolved for proper positioning or for rotating the work for cylindrical grinding. The spring 147 renders it possible for quick removal and replacement of work while maintaining a force between the centering elements. The element 136 is also adjustable as indicated by spline 134a on rod 134 to vary the spacing between points of pins 139 and 145, for supporting various types of work.

While the centering elements are shown to be supported on a post mounted on the integral member 130 it will be clear that the post 14 with centering elements etc. may be used in the sleeve 73 or 96 of the couplers 70 and 94, Figs. 2 and 6.

In Figs. 10 and 11 I have shown another form on which the centering elements may be mounted. In this form the supporting post 74 carries a shaft 150 which in turn carries brackets 151 and 156 for supporting rod 153 and a slideable bracket 152 which supports rod 154. The rods 150, 153 and 40 154 are parallel to each other, the brackets having means for locking the rods in desired relationship. The rod 154 supports centering elements 135a and 136a similarly as indicated in Figs. 8 and 9, except here they are shown disposed horizontally.

48 It will be noted that the rod 153 is disposed beneath rod 154. The purpose of rod 153 is to provide a fixed bearing surface for proper retention of rod 154 and thereby centering elements 135a and 136a. This bearing relationship is obtained by means of a hard pin depending from the slide 152 on bar 150. The pin 155 bears against the upper side of rod 153. This supporting arrangement provides a steadier support for the work and enables the operator to shift the rod 154 relative to the supporting post 74 with assurance that when pin 155 engages rod 153 it is in the proper vertical or angular position.

The post 74 is shown to include a series of key ways 174 whereby a quick vertical positioning of the posts may be facilitated with respect to the socket 157 of coupler 158 (similar to coupler 70, Figs. 1 to 4). As shown in Fig. 11 a key 175 received in one of the key ways of post 174 may engage notches 160 or notches 161 depending on the desired angular position of post 74. As shown in Figs. 6 to 8 the post 74 may have this key adjustment feature in addition to the socket locking element 173a. If desired other supporting rods such as, for example, rod 109, Figs. 5 and 6, may also include this key way adjustment feature.

In Fig. 12 I show a work supporting bracket that may be used in the place of slide bracket 152 (and also rod 153) for supporting a vertical

post similar to post 74. This bracket includes a sleeve 164 to receive rod 150, the bracket including a depending pin 165, the same as 155 in bracket 152, to bear upon rod 153. The bracket further includes a socket 166 for reception of vertically disposed posts used in conjunction with other forms of work supporting structures.

While I have shown and described the principles of my invention in connection with specific apparatus it will be clear that many variations and separate sub-combinations may be made without departing from the invention. It should therefore be understood that the embodiments shown are illustrative of the invention only.

I claim:

1. In a work shaping apparatus having a spindle and a work shaping wheel carried thereby, a member rockable about an axis parallel to said spindle, said member having a portion coaxially disposed with respect to said axis, a post, a coupling element provided with a first sleeve receivable on said portion, means for securing said first sleeve in desired position thereon, a second sleeve disposed at right angles to said first sleeve to receive said post, and means to secure said post in desired position in said second sleeve, said post having a transverse opening therein, a work supporting means including a rod receivable through said opening and means for adjustably securing said rod to said post, whereby rocking movement of said member moves said work supporting means back and forth relative to the working surfaces of said wheel.

2. A work shaping apparatus according to claim 1 wherein said work supporting means includes a second rod and a plurality of spacer elements receivable on said second rod, and means for securing work stock on said second rod, certain of said spacer elements being used to determine the position of said work stock on said rod.

3. A work shaping apparatus according to claim 1 wherein said coupling element includes means connecting said second sleeve in offset relation with respect to said first sleeve whereby said post is adjustable axially through said second sleeve without interference by said first sleeve.

4. A work shaping apparatus according to claim 1 wherein the rockable member includes means for axially adjusting said portion while allowing said portion to be rocked about said axis.

5. In a work shaping apparatus having a spindle and a work shaping wheel carried thereby, a member rockable about an axis parallel to said spindle, a post, a coupling element for supporting said post on said member with the axis of said post transverse to the axis of said member, a work supporting means carried by said post including a rod extending outwardly from said post, a plurality of spacer elements receivable on said rod, and means for securing work stock on said rod, certain of said spacer elements being used to determine the position of said work stock on said rod.

6. In a work shaping apparatus having a spindle and a work shaping wheel carried thereby, a member rockable about an axis parallel to said spindle, a post, a coupling element for supporting said post on said member with the axis of said post transverse to the axis of said member, a work supporting means carried by said post including a rod extending outwardly from said post, a plurality of spacer elements receivable on said rod, means for securing work on said rod, certain of said spacer elements being used to determine

the position of said work on said rod, a positioning device for said work including an elongated element, a sleeve securable on said post having means to support said element transversely with respect to the axis of said post, a work locating finger, and means on said element for adjustably securing said finger thereto.

7. In a work shaping apparatus having a spindle and a work shaping wheel carried thereby, a member rockable about an axis parallel to said spindle, a post, a coupling element for supporting said post on said member with the axis of said post transverse to the axis of said member, a work supporting means carried by said post, said work supporting means including two centering elements and means for adjustably supporting said centering elements at spaced points.

8. In a work shaping apparatus having a spindle and a work shaping wheel carried thereby, a member rockable about an axis parallel to said spindle, a post, a coupling element for supporting said post on said member with the axis of said post transverse to the axis of said member, a work supporting means carried by said post including a rod extending outwardly from said post, said rod including a transverse opening therethrough and said work supporting means further includes a second rod receivable in the opening of the first mentioned rod, two centering elements, and means for adjustably securing said centering elements at spaced points on said second rod.

9. In a work shaping apparatus having a spindle and a work shaping wheel carried thereby, a member rockable about an axis parallel to said spindle, a post, a coupling element for supporting said post on said member with the axis of said post transverse to the axis of said member, a work supporting means carried by said post including a rod extending outwardly from said post, a second rod carried by the first mentioned rod at an angle thereto, and means for supporting work stock on said second rod.

10. In a work shaping apparatus having a spindle and a work shaping wheel carried thereby, a carriage, a bar located remote and parallel to said spindle for guiding the carriage for movement in directions parallel to said spindle, said carriage having a rocking member the axis of which is parallel to said spindle, a post, a coupling element provided with a first sleeve receivable on said rocking member, means for securing said first sleeve in desired position thereon, a second sleeve disposed at right angles to said first sleeve to receive said post, means to secure said post in desired position in said second sleeve, and means for adjustably supporting work on said post, whereby rocking movement of said rocking member causes said post and work supported thereon to be rocked back and forth relative to said wheel.

11. In a work shaping apparatus, a post, a work supporting means carried by said post, said work supporting means including two parallel rods carried by said post, a work supporting member, bearing means to support said member on one of said rods, and means on said member to bear against the other of said rods.

12. In a work shaping apparatus, three rods, means to maintain said rods in parallel relation, said means including a bracket to support two of said rods in spaced relation, said bracket being rotatable and movable lengthwise of one of said two rods, and means on said bracket for bearing against the third rod.

13. In a work shaping apparatus, a post having a transverse opening therethrough, a rod disposed through said opening, a pair of brackets mounted in spaced relation on said rod, said brackets having transverse openings therethrough, a second rod disposed in said openings, and a third bracket slideably mounted on the first mentioned rod and having a part engageable with said second rod, said third bracket having means for supporting work thereon.

14. In a work supporting apparatus according to claim 13, wherein the means for supporting work on said third bracket includes a third rod supported by said bracket, and a pair of centering elements carried in spaced relation by said third rod.

15. In a work shaping apparatus having a spindle and a work shaping wheel carried thereby, a member rockable about an axis parallel to said spindle, a post, a coupling element for supporting said post on said member with the axis of said post transverse to the axis of said member, a work supporting means carried by said post, said work supporting means including a first rod extending transversely thereof, means for supporting a second rod in parallel relation to said first rod, a work supporting member carried by said first rod and adjustable lengthwise thereof, said supporting member being adapted to engage said second rod to ensure proper angular relation for different positions along said first rod.

16. In a work shaping apparatus having a spindle and a work shaping wheel carried thereby, a member rockable about an axis parallel to said spindle, a post, a coupling element for supporting said post on said member with the axis of said post transverse to the axis of said member, a work supporting means carried by said post, said work supporting means including a first rod extending transversely of said post, a pair of brackets mounted in spaced relation on said first rod for supporting a second rod parallel to said

first rod, a third bracket mounted for movement lengthwise of said first rod and having a part adapted to bear against said second rod, and means for supporting work from said third bracket.

17. In a work shaping apparatus having a spindle and a work shaping wheel carried thereby, a member rockable about an axis parallel to said spindle, said member having a portion coaxially disposed with respect to said axis, a post, a coupling element provided with a first sleeve receivable on said portion, means for securing said first sleeve in desired position thereon, a second sleeve disposed at right angles to said first sleeve to receive said post, and means to secure said post in desired position in said second sleeve, said post having a transverse opening therein, a work supporting means including a rod receivable through said opening, means for supporting a second rod parallel to the first mentioned rod, a part slideably supported on one of the rods and adapted to engage the other of said rods, said part having means to support work thereon, whereby said work may be moved lengthwise of said rods while rocking movement of said member moves said work back and forth relative to the working surfaces of said wheel.

EMIL F. HAGER.
